HYMAN SHAPIRO, OF BROOKLYN, NEW YORK, ASSIGNOR TO THE M. PROPP CO. INC.,
OF NEW YORK, N. Y., A CORPORATION OF NEW YORK

ELECTRIC SOCKET

Original application filed February 6, 1925, Serial No. 7,207. Divided and this application filed July 20, 1926. Serial No. 123,603.

This invention relates to detachable electric fittings, such as switch type, duplex, lamp-socket, plug fittings adapted to receive a pair of electric bulbs or a pair of connectors of other electric apparatus.

One object of the invention is to provide an improved, selectively operated, push button switching means which is especially adapted to be incorporated in lamp-socket, 10 plug fittings of the character described.

Another object of the invention is to provide a device of the character described including an improved push-button switching mechanism, and comprising few and simple 15 parts which may be quickly and easily assembled, cheap to manufacture yet neat and attractive in appearance, and practical and efficient in operation to a high degree.

Other objects of this invention will in part 20 be obvious and in part hereinafter pointed out.

This application is a division of my co-pending application Serial No. 7,207, filed Feb. 6, 1925, and certain features herein 25 shown and described are shown, described, and claimed in my said co-pending application and in my co-pending application Serial No. 123,602 filed simultaneously herewith, now Patent No. 1,646,499.

The invention accordingly consists in the features of construction, combinations of elements, and arrangement of parts which will be exemplified in the construction herein-after described, and of which the scope of 35 application will be indicated in the following claims.

In the accompanying drawing, in which is shown one of the various possible illustrative embodiments of this invention,

Fig. 1 is a plan view of a completely assembled socket.

Fig. 2 is a transverse section taken on line 40 2-2 in Fig. 1 showing one section of the socket and the push button switching mechanism mounted therein.

Fig. 3 is a sectional detailed view taken on line 3-3 in Fig. 2.

Fig. 4 is a bottom plan view of the exteriorly threaded shell cap which assists in holding the sections of the socket in assembled relation.

Fig. 5 is a fragmentary view showing a modified form of push button switching mechanism.

Fig. 6 is an enlarged detailed sectional view taken on line 6-6 in Fig. 5.

Referring in detail to the drawing, 10 denotes an electric lamp socket embodying the invention. Said socket is seen to comprise two mating, molded, insulating sections 15 and 16, each including an intermediate body portion 17 of substantial solidity and on opposite sides of such intermediate portion, a pair of short arms hollowed out to provide internally threaded socket portions 18, 18 disposed approximately at right angles to each other. Forming a continuation of the body portion of each member is a plug portion 19 which may be cut away internally as indicated by the hollow portion 20. When the two sections 15, 16 are placed together in mating relationship, the two hollow neck portions cooperate to provide a plug of oval exterior shape upon which fits an exteriorly threaded shell 21 provided with an inwardly turned flange 22 having an oval opening therein to prevent rotation of the shell on the neck of the socket. By virtue of this construction, I am able to eliminate the necessity for exteriorly threading the socket neck and simply slip the shell in place and hold it against rotation on the neck by the non-circular flange 22. Suitable supplemental means may be provided for anchoring the shell 21 against rotation relative to the neck of the socket member, such for instance, as by soldering the shell 21 to a conducting member 75, as will hereinafter appear.

As an additional precaution against the accidental separation or relative displace- 90

ment of the two mating sections 15 and 16, I preferably employ annular metallic bands 50 encircling the extremities of the short arm portions thereof, said bands being frictionally fitted or otherwise firmly but preferably detachably secured in place. The two sections of the duplex sockets are thus secured together at their three outermost parts and are accurately maintained in proper mating relationship.

It will be understood that the shell portion 21 is screwed into a suitable outlet plug in the wall or in the socket of an ordinary electric light fixture and the sockets 18 receive electric bulbs or connections for other electrical apparatus. I equip the sockets 18 with contact members to engage the said shell and the central terminal contact of an electric lamp having the ordinary Edison base.

In the form of the invention shown in the drawing, the switch mechanism for the lamps is seen to comprise independently operable push button switches, one connected in a lead 25 to each lamp socket 18, the other leads comprising conducting members 75 projecting through the body of the moldings. Said members are soldered to the shell 21 at one end 75^a and include fingers 76 at their other ends projecting into the bases of the lamp sockets 18 and constituting the central contacts thereof. The central current carrying member 77 is provided with a tongue 78 projecting through and beyond the neck of the 30 molding and constituting the central plug contact. Its intermediate portion is secured in cooperating grooves 79 of the two molded members 15, 16 and its resilient end 80 is accommodated in a recess 81 formed by operating recesses in the molded sections of the body, and extends at one side of said recess longitudinally of the wall of one of the 35 sockets 18. A second conducting member 82 has one end secured in the same grooves 79 which retain member 77 and terminates in a free end 83 disposed in the recess 81 and longitudinally of the wall of the other socket 18. The push button switches are in the nature of rods 84 extending through the recess 40 81 and including ends which project through and are exposed exteriorly of the body portion of the socket. The intermediate portions of the rods 84 are provided with shoulders 85 adjacent cam surfaces 86 which are adapted to engage with spring fingers 80, 83, and lift them onto the shoulders 85 as the rods 84 are axially shifted. In the drawing, I have shown the left hand rod 84 in the "off" position and the right hand rod 84 in the "on" 45 position, in which the corresponding spring finger 80 has been pressed against the shell contact of the enclosed lamp, or plug, (not shown), to complete circuit thereof. It will be noted that member 16 is equipped 50 with pockets 87 therein for accommodating

the shoulders 85 when the rods 84 are pushed to release the spring fingers 80 and 83 which will snap to the position shown at the left in Fig. 3 to open circuit.

As seen from Fig. 2, the projecting spring end 78 of the central plug contact is not likely to be strained, or to break at the hinge line when pressed into the outlet socket since the length of spring metal integral therewith and longitudinal of the plug is free to flex within the hollow structure of the plug thereby permitting such accommodation without strain, and affording effective spring contact engagement in the outlet socket.

Figs. 5 and 6 illustrate a modification of the push button switch push rod 90 in which the rod is of insulating material and of circular cross section and provided at its central portion with a diametrically extending slot 91 in which a swivelled cam 92 is secured upon a rivet 93. These rods 90 may be conveniently substituted for the rods 84, the cams of course, taking the place of the shoulders 85 and being adapted to project tongues 80, 83, into contact making position, by a toggle lever action with their supporting rods. Preferably a pin 84^a in the path of the cam renders this toggle action positive so that as the push bar is moved to switchclosing position, carrying with it the pivot of the cam, the cam is turned by the pin 84^a and moved to its full throw position urging the spring terminal arm into contact closing position. Upon release, a rapid snap action is had since pressure on the rod to move the cam off its dead center position results in the spring contact member quickly returning the parts to their normal open circuit position.

While I have shown duplex socket members embodying in detail the construction of a push button type of switch, it is understood that various methods of securing the complementary socket sections together may be employed but the method shown in the drawing and described above is seen to greatly expedite assembling the device in that it obviates the necessity of exteriorly threading the plugs of the sockets or accurately fitting the shells on the plug portion. The current carrying members or conducting arms are accommodated in complementary grooves formed in the complementary sections of the duplex socket, that is to say, the contact arms 75 and 77 and conducting strip 82 are simply laid in place in their respective grooves when the two sections of the socket are assembled and require the use of no securing device, such as screws, rivets, or the like.

It will thus be seen that there is provided a device in which the several objects of this invention are achieved, and which is well adapted to meet the conditions of practical use.

As various possible embodiments might be made of the above invention, and as various

changes might be made in the embodiment above set forth, it is to be understood that all matter herein set forth or shown in the accompanying drawing is to be interpreted as 5 illustrative and not in a limiting sense.

Having thus described my invention, I claim as new and desire to secure by Letters Patent:

1. A duplex socket member including a 10 pair of complementary sections of molded insulating material cooperating to provide a pair of unlined sockets, terminal devices in the bottoms of the sockets, spring arms mounted for movement through the sides of 15 the sockets and a pair of independent push buttons positioned between said sockets adapted to be longitudinally operated to move the arms into contacting position within the sockets, said push buttons comprising rods 20 having their opposite ends mounted in and projecting beyond mating openings in the two members of the duplex socket and including enlargements at their intermediate portions engageable with the arms to move them into 25 contact position, said enlargements serving as stops for limiting the movement of the rods in both directions, said duplex socket members, each having a recess therein, normally housing the spring terminal arms and providing clearance for the movement of the enlarged portions of the rods.

2. In a push button switch, the combination with a spring finger normally held in one extreme position by its inherent resiliency, 35 of an axially movable push rod, a cam swivelled within the rod and engageable with the finger whereby a toggle lever action is exerted between the push rod and cam as the rod is moved in one direction to flex the finger.

40 3. In a push button switch, an axially movable push rod, a cam pivotally mounted therein, a spring contact finger exerting pressure on the cam and tending to maintain the rod in one extreme position, and means whereby 45 movement of the rod toward the other position effects movement of the spring finger through the intermediacy of the cam, and locks said finger in its shifted position when the cam passes its dead center.

50 In testimony whereof I affix my signature.
HYMAN SHAPIRO.
